[57] CLAIM

The ornamental design for a boat, as shown and described.

DESCRIPTION

FIG. 1 is an elevational side view of the right side of the boat, the opposite side being the same. The boat is illustrated in an attitude in which the boat rests in water;

FIG. 2 is a rear view of the boat;

FIG. 3 is a front view of the boat;

FIG. 4 is a top view of the boat; and,

FIG. 5 is a bottom view of the boat.
